United States Patent Office.

JAMES McLAUGHLIN, OF DUNCANNON, PENNSYLVANIA.

Letters Patent No. 64,124, dated April 23, 1867.

IMPROVED RAILWAY SWITCH.

The Schedule referred to in these Letters Patent and making part of the same.

TO ALL WHOM IT MAY CONCERN:

Be it known that I, JAMES McLAUGHLIN, of Duncannon, in the county of Perry, and State of Pennsylvania, have invented a new and improved Railroad Switch; and I do hereby declare that the following is a full, clear, and exact description thereof, which will enable those skilled in the art to make and use the same, reference being had to the accompanying drawings, forming part of this specification.

This invention relates to a new and improved railroad switch, whereby I am enabled to dispense with the use of frogs, and a very reliable switch obtained. This invention is an improvement on a switch previously invented by me, and the subject of another application. The present invention consists chiefly in the employment or use of elastic switch-rails in lieu of the pivoted rails hitherto used, and in a novel construction and arrangement of parts, hereinafter fully shown and described. In the accompanying sheet of drawings

Figure 1 is a plan or top view of my invention.

Figure 2, a transverse section of the same taken in the line *xx*, fig. 1, and looking in the direction indicated by arrow 1.

Figure 3, a sectional plan or top view of a portion of the switch-rails.

Figure 4, a transverse section of the switch-rails taken in the line *yy*, fig. 1.

Similar letters of reference indicate corresponding parts.

A A represent the rails of a main track, and B B the rails of a branch track. C C represent the switch-rails, placed on the ties in V-form, and connected at their diverging ends to three ties, E, by means of spikes, a. The spiked portion of the switch-rails extend about one third of their length. The converging ends of the switch-rails are connected together by a bolt, F, which passes through an oblong slot, b, in said ends of the rails, as shown clearly in fig. 3. The portion of the switch-rails included between the connected ends and the spiked portion, and which comprises about two-thirds of their length, is the yielding or spring portion, the elasticity being sufficient to admit of the connected ends of the rails being brought or adjusted in line with the inner main or inner branch rail as desired, and these connected ends of the switch-rails work in a chair, G, attached to a tie, H; said chair being constructed with a slot, c, of such a width as to admit of this movement of the switch-rails, and at the same time serve to limit the movement of the same so that they cannot be adjusted beyond either of the inner rails of the main and branch tracks. This will be fully understood by referring to fig. 1. The elastic or disengaged portions of the switch-rails are connected by cross-rods, d, the ends of the latter fitting in oblong holes, d², in the rails, to admit of a free working or springing of the rails in adjusting them. These cross-rods are provided at each end with a shoulder to bear against the inner sides of the rails, said shoulders being formed by the tenons on the cross-rods, which tenons pass into the holes. For the same reason the slot *b*, in the ends of the rails C, through which the bolt E passes, is made oblong. The switch-rails, at a point near their connected ends, are attached to a sliding bar, I, one end of which is connected to a crank, e, on a shaft, J, and the opposite end passing underneath a bar, f, attached to the tie H and to an adjoining tie, K. This bar f prevents the sliding bar I from moving vertically, and keeps the connected ends of the rails C C snugly down on the tie H within the slot *c* in the chair G. Besides the slotted chair G spikes *g* are driven into the tie K, and into the two adjoining ties L L, to prevent an undue movement of the switch-rails either to the right or left, by springing or spreading, a contingency which might occur under the action of the wheels of a locomotive. By this arrangement it will be seen that the switch-rails C C may be adjusted either in line with the main or the branch track, and in case the switch-rails be adjusted in line with the branch track, the switch-rails will be out of parallel with the outer rail of the main track, the former being nearer the outer rail of the main track at their free or disengaged ends, so that in case a train be moving on the main track in the direction indicated by arrow 1, and the switch-rails in line with the branch track the switch-rails will under the action of the wheels of the locomotive be moved in line with the main track. The same result will attend the moving of a train on the branch track when the switch is in line with the main track.

I claim as new, and desire to secure by Letters Patent—

The movable elastic frog continuous with and forming part of the adjoining rails C C, their converging slotted ends joined together in the slotted chair G, by means of the bolt F, their elastic or disengaged portion connected together by means of the cross-rod d, in combination with the main rails A A, branch rails B B, and operated by means of the crank e and sliding bar I, substantially as herein shown and described for the purpose specified.

JAMES McLAUGHLIN.
